(Cl: D26—13)

FIG. 1

FIG. 2

FIG. 3

FIG. 4

FIG. 5

FIG. 6

Fig. 1 is a perspective view of a thermostatic control unit or similar article, showing my new design;

Fig. 2 is a front elevational view;

Fig. 3 is a side elevational view, the opposite side being substantially a mirror image thereof;

Fig. 4 is a rear elevational view;

Fig. 5 is a top plan view; and

Fig. 6 is a bottom plan view thereof.

The broken line fragmentary showing of a connecting cord and a representative coffee maker or similar article in Fig. 1 is for illustrative purposes only, and has been

omitted from the remaining figures for convenience in illustration.

I claim:

The ornamental design for a thermostatic control unit or similar article, as shown and described.
